UNITED STATES PATENT OFFICE.

FRANK W. HAWKINS, OF BUTLER, PENNSYLVANIA, ASSIGNOR OF ONE-HALF TO GEORGE W. FECHTER, OF BUTLER, PENNSYLVANIA.

AUTOMATIC SIGNAL FOR RAILROADS.

1,289,468.

Specification of Letters Patent.

Patented Dec. 31, 1918.

Application filed March 1, 1917. Serial No. 151,826.

To all whom it may concern:

Be it known that I, FRANK W. HAWKINS, a citizen of the United States, residing at Butler, in the county of Butler, in the State 5 of Pennsylvania, have invented an Automatic Signal for Railroads, of which the following is a full and complete description.

In order to safeguard the operation of trains the principal railroads of the country 10 are now provided with what is termed the "block system," in which the road is divided into blocks or sections of track provided with electrical devices, usually operated automatically, and including semaphores or 15 other visual signals, whereby the engineer of a moving train is advised of the conditions prevailing in each successive block or section before entering the same as to whether or not it is clear and safe; but the 20 successful operation of this system depends upon the watchfulness of the engineer, for it is his duty to make a mental note of each block signal he approaches so as to be governed in the operation of his train thereby. 25 Therefore, even with such an admirable system of train-control trains have been run past "danger" signals and into accidents through the carelessness of the engineer in failing to observe the danger-signal. 30 Appreciating the imperfection of the ordinary block system, especially in the particular above noted, it is the purpose of my invention to supplement the usual visual signals by an audible signal or whistle in the 35 cab of the locomotive and adapted for operation automatically in conjunction with the semaphores, whereby when the latter is in danger position a device alongside the track will be moved into position to operate cer- 40 tain mechanism on the locomotive to cause the whistle to be blown and thus attract the attention of the engineer to the prevailing conditions in a positive and sure manner.

A further object of my invention is to 45 provide operating mechanism for this general purpose of such construction and arrangement that should any of the parts of the system get out of order or become broken the whistle will be automatically operated 50 to give an alarm.

These and other objects hereinafter explained are attained by the particular construction of mechanical devices carried by the locomotive and coöperating with certain 55 track devices; all as hereinafter particularly

described and specifically set forth in the appended claims.

In the accompanying drawings:

Figure 1 is a side view illustrating the general application of my invention. 60

Fig. 2 is a front view showing the arrangement of the valve-operating mechanism on the front part of the locomotive.

Fig. 3 is an enlarged sectional view of the valve controlling the operation of the whistle, and including the mechanism. 65

Fig. 4 is a detail sectional view of the valve taken at right angles to the section Fig. 3, to show the construction of the lower end of the stem of the valve. 70

Fig. 5 is a detail sectional view of the trip device located alongside the track and operated in conjunction with the semaphores of the block system.

Figs. 6, 7 and 8 are detail views illustrating a modification, hereinafter referred to. 75

As will be understood, my invention is adapted for application to a railroad in which the locomotive or train has the usual air-brake installation and the road or track 80 provided with a conventional type of block system operating semaphore signals, and as their general construction and operation are well known full illustration and description thereof herein is obviously unnecessary, particularly as the devices I employ for sounding an audible alarm in the cab of the locomotive are supplemental thereto and coöperate with certain parts thereof only. 85

In carrying out my invention I provide as 90 an important part thereof a reciprocating valve 9, located on the locomotive, A, preferably at the front end thereof, and interposed between an air-pipe 10 from the usual compressed-air reservoir (not shown) of the 95 air-brake system and an air-pipe 11 extending from said valve into the cab of the locomotive where it is connected to an ordinary type of whistle, 12, adapted to be sounded when the valve is opened. This 100 valve is operated in the present instance by a double crank-shaft 13 connected to the stem 23 thereof and in turn operated by a second double crank-shaft 14 having its depending member 14' terminating in a shoe 105 15, traveling with the locomotive at the outer side of either rail, a, and adapted to be struck by a tappet 16 operating reciprocally in a cylindrical casing 17 in fixed position alongside the track. 110

The operating crank-shafts 13 and 14, hereinbefore mentioned, are mounted on suitable parts of horizontal beams at the front of the locomotive, and are journaled in bearings 18, locating the air control valve 9 so that it may be operated from either side of said locomotive. It will be understood that the crank ends of the respective shafts of each set are so proportioned that the throw 10 of the depending member or operating-arm 14^a by the tappet 16 will impart the required extent of reciprocation to the valve; the swinging movement of the crank-arms 13^a producing a perpendicular movement of the 15 reciprocating piston of the valve by means of the particular connection hereinafter described.

The casing of the air-control valve 9, in which the piston or reciprocating-valve 20 operates, is provided near its upper end with an inlet-valve 21, to which the air-pipe 10 from the compressed-air reservoir is connected, and in its top with an outlet-port 22 to which the air-pipe 11 leading to the 25 whistle is connected; the piston in operation uncovering the inlet 21 when lowered (see dotted lines Fig. 4) to establish communication between the inlet and outlet ports, and covering said ports when raised against the 30 top of the casing. The stem 23 of the valve depends through the bottom of the casing for connection with the crank-arms 13^a, 13^a, by pin 25, and a space is left between the piston and bottom of the casing to receive a 35 light spring 26, which assists merely in raising said piston. In order to hold the piston to its lowermost position, and maintain the valve open, I provide a spring-actuated catch or plunger 27, mounted in a tubular 40 extension 9^a at one side of the valve-casing, and adapted to engage in a notch or recess 20^a in said piston. This plunger or catch is projected into the recess by a spring 28, and the stem of said plunger projects 45 through and beyond the tubular extension 9^a, terminating in an eye 27^a to which a cord 29 is connected and led therefrom through suitable guide-eyes on the locomotive to the 50 cab within easy reach of the engineer. By this arrangement when the air-control valve is opened by the operation of the trip devices hereinbefore described the warning whistle will continue to blow until the valve is released; therefore should the engineer be 55 incapacitated from any cause, preventing him from heeding the warning signal, any other member of the train crew noting the continued blowing of the warning would be prompted to investigate; thus providing a 60 safe-guard which would be effective in an emergency of this character, whereas the ordinary semaphore warning would be likely to fail. In other words the whistle warning is given in a positive and sure manner 65 and will continue until heeded and checked.

As the crank-member 13^a of the operating crank-shaft 13 has a lateral swinging movement, imparted by the second operating crank-shaft 14 which is struck by the tappet, the connecting-pin 25 engages in a segmental 70 slot 24 in the lower end of the valve-stem 23, and to provide for this slot said lower end of the valve-stem is enlarged or widened, as shown. The normal location of the pin 25, with respect to the slot, when the valve 75 is closed, is at the center of said slot, and when the arm or arms 13^a swing to either side when either shoe 15 is struck the pin rides upon the lower wall of the slot 24 and draws the stem downward, opening the 80 valve, as will be clearly understood by reference to Fig. 4 of the drawings. Of course when either set of crank-arms are operated the other set is also moved or actuated, though unnecessarily, by reason of the pin 85 25 connecting both crank-arms 13^a, 13^a; but as hereinafter set forth I provide an arrangement by which one set may remain stationary while the other is operated.

This modification is accomplished by the 90 construction illustrated in Figs. 6, 7 and 8, wherein the valve-stem is forked and provided with two slotted members 23^a, 23^a, each having a segmental slot 30 and an upwardly projecting communicating slot 31 at 95 the center of said segmental slot. In this arrangement the crank-arms 13^a are connected independently to individual members 23^a each by a pin 32, whereby when either arm is swung laterally its connecting-pin 32 100 will work to draw upon the valve, while the other or companion crank-arm 13^a may remain stationary as its pin 32 will enter the recess or slot 31 in the valve-stem member to which it is connected. By this arrangement I provide also for automatically 105 opening the valve in case the shoe 15 should become broken off, for each crank-arm 13^a may be influenced by a spring 35 serving to throw said arm, and consequently open the 110 valve, when the operating crank-shafts are relieved of the weight of the shoe. This spring, one for each crank-arm 13^a may be attached to an eye 36 on a part of the locomotive and to the outer end of the crank-arm and of such strength as to require the 115 weight of the shoe to maintain the valve closed or said crank-arm in vertical position.

The tappet for operating either set of 120 crank-shafts or valve-operating mechanism is located at one side of the track, preferably the outer side in case of a double-track, and is operated in one direction by a solenoid 17^a, and in the other direction by a spring 125 19, the stem or core 16^a from the tappet depending into the coil, whereby in the present instance the tappet-member is drawn upon or lowered when the solenoid is energized by the circuit, hereinafter referred to, 130

and projected into the path of the shoe by the spring when said circuit is open. The solenoid is electrically connected to the semaphore, B, so as to operate in conjunction therewith, by means of wires *c* and *d*, and in the present instance the connection is such that the circuit will be closed—lowering the tappet—when the semaphore is in “safe” position, and open—projecting the 5 tappet into the path of the shoe—when said semaphore is in “danger” position; whereby in case the circuit should become broken from any cause the tappet would be automatically moved by the spring to operative 10 position with respect to the shoe. As will be noted this is another safeguard to insure a warning to the engineer in case the arrangement for operating the tappet should get out of order.

15 20 For the proper and efficient operation of a supplemental warning of this character it is of course necessary that the parts should work properly at all times, for when it is installed it is possible that the engineer 25 will come to rely more on the audible signal than watchfulness of the semaphores of the block system, and in some instances the semaphores may be dispensed with. It is therefore a very important desideratum 30 of an arrangement of this kind that a warning be given in case some part of the mechanism should become broken or disrupted. I have devised with this contingency in view, and it will be seen that the requirements have 35 been fulfilled in very great measure.

The operation of the warning apparatus will be readily understood from the foregoing, in connection with the accompanying drawings; for when the semaphore of 40 the block system is in the position indicating a clear track ahead or safe conditions in the next block the solenoid will be energized to lower the tappet out of the path of the shoe carried by the locomotive, so that 45 the train will pass without operation of the valve 9 controlling the admission of air to the warning whistle 12. On the other hand, should the semaphore be in “danger” position the solenoid would be deenergized permitting 50 the spring to raise the tappet into the path of the shoe on the operating member carried by the locomotive so that said shoe will strike the tappet and open the air-control valve admitting air to the whistle, 55 the spring-actuated plunger then engaging the piston of the valve to hold it to open position until released by the engineer. Therefore, even should the engineer fail to observe the semaphores as he proceeds with 60 his train from one block to another the whistle would be blown to warn him in case of a “danger” condition.

It will be understood, of course, that the lower ends of the shoes are on a plane a 65 little higher than that of the rails, so that

they may clear cross-overs and switches, and therefore the tappet devices project, as shown in the drawings. Also, as shown in the drawings, a single tappet device is employed with each track, requiring a duplication 70 of the operating crank-shafts to insure operation of the air-control valve when the locomotive is traveling either forward or backward. However, instead of duplicating the operating crank-shafts the electrically-operated tappet device could be duplicated; 75 that is, one provided at each side of the track, in which instance but a single set of said operating crank-shafts would be required, and of course would then be operated by one or the other according to whether the locomotive was traveling forward or backward. Furthermore, this latter arrangement may permit of the use of a single operating crank-shaft, provided at 80 one end with the operating crank-arm, as 13^a, connected to the valve-stem, and at the other end with the depending operating-member, as 14^a, carrying the shoe 15, and of course in this instance the form of slot in the valve- 85 stem shown in Fig. 4 would be sufficient, although that shown in Fig. 7 could be used without affecting the efficiency of operation, inasmuch as in moving the valve-piston the pin bears upon the bottom wall of the slot. 90 95

It will be readily seen, therefore, that the arrangement is susceptible of changes without materially altering the operation, and I desire protection in whatever changes may be suggested in the practical operation of 100 the apparatus, within the scope of my claims.

Though I have described the audible signaling mechanism as applied in connection with or supplemental to the usual semaphores, it will be understood, of course, that 105 it may be used alone in place of the same, the usual electric connections with the block system being such that it will operate the solenoid when a “danger” condition exists, instead of operating both the semaphore and solenoid, as hereinbefore described.

Having described my invention, I claim:

1. In an automatic signal for railroads, the combination of a whistle carried by the locomotive, a compressed air supply pipe 115 leading from a suitable supply to said whistle, a valve located on the locomotive to intercept said air supply and having a reciprocating piston, a stem depending from the valve-piston and provided at its lower 120 end with a bifurcated portion each member of which has a transverse segmental slot and a vertical slot extending upwardly from the center of said segmental slot, and independent crank shafts at opposite sides of 125 the valve each having an arm connected by a pin to the slots in the members of the bifurcated portion of the valve-stem, respectively, whereby either crank shaft may be moved for operation and the other remain 130

stationary; together with means for operating the crank-shafts.

2. In an automatic signal for railroads, the combination of a whistle carried by the locomotive, a compressed air supply pipe leading from a suitable supply to said whistle, a valve located on the locomotive to intercept said air supply and having a reciprocating piston, a stem depending from the valve-piston and provided at its lower end with a bifurcated portion each member of which has a segmental slot and a vertical slot extending upwardly from the center of said segmental slot, independent crank-

shafts at opposite sides of the valve each 15 having an arm connected by a pin to the members of the bifurcated portion of the valve-stem, respectively, said pins working in the slots in said members, a spring connected to each crank-shaft for normally 20 opening the valve, and a weighted shoe forming an operating member for each crank-shaft and acting on the latter to hold said valve normally closed.

FRANK W. HAWKINS.
